(57) **CLAIM**

The ornamental design for a puzzle board with foldable legs as shown and described.

DESCRIPTION

FIG. 1 is a perspective view of a puzzle board with foldable legs showing my design, with the legs being in a deployed configuration;

FIG. 2 is another perspective view of the puzzle board with foldable legs, with the legs being in a folded configuration; FIG. 3 is a front view of the puzzle board with foldable legs as shown in FIG. 1;

FIG. 4 is a rear view of the puzzle board with foldable legs as shown in FIG. 1;

FIG. 5 is a left view of the puzzle board with foldable legs as shown in FIG. 1;

FIG. 6 is a right view of the puzzle board with foldable legs as shown in FIG. 1;

FIG. 7 is a top view of the puzzle board with foldable legs as shown in FIG. 1;

FIG. 8 is a bottom view of the puzzle board with foldable legs as shown in FIG. 1;

FIG. 9 is perspective view of the puzzle board with foldable legs, with the legs being in a deployed configuration and drawers on the four sides of the puzzle board being pulled out;

FIG. 10 is a front view of the puzzle board with foldable legs as shown in FIG. 9;

FIG. 11 is a rear view of the puzzle board with foldable legs as shown in FIG. 9;

FIG. 12 is a left view of the puzzle board with foldable legs as shown in FIG. 9;

FIG. 13 is a right view of the puzzle board with foldable legs as shown in FIG. 9;

FIG. 14 is a top view of the puzzle board with foldable legs as shown in FIG. 9; and,

FIG. 15 is a bottom view of the puzzle board with foldable legs as shown in FIG. 9.
